Primary Examiner—Holly H. Baynham

(74) Attorney, Agent, or Firm—Jeffrey D. Peterson;
Michael Best & Friedrich LLP**CLAIM**

The ornamental design for a pass through concrete anchor, as shown and described.

DESCRIPTION

FIG. 1 is a top view of the concrete anchor.

FIG. 2 is a side view of the concrete anchor; and,

FIG. 3 is a perspective view of the concrete anchor.

The present application is directed to the design illustrated in the drawings. The broken line portions of the disclosure are for illustrative purposes only and form no part of the claimed design.
